UNITED STATES PATENT OFFICE.

EDGAR L. DEGREE, OF BURLINGTON, VERMONT, ASSIGNOR OF ONE-HALF
TO JAMES R. LOCKWOOD, OF BURLINGTON, VERMONT.

SAND-GUARD.

SPECIFICATION forming part of Letters Patent No. 731,345, dated June 16, 1903.

Application filed December 8, 1902. Serial No. 134,364. (No model.)

To all whom it may concern:

Be it known that I, EDGAR L. DEGREE, a citizen of the United States, residing at Burlington, in the county of Chittenden and 5 State of Vermont, have invented certain new and useful Improvements in Sand-Guards; and I do declare the following to be a full, clear, and exact description of the invention, such as will enable others skilled in the art 10 to which it appertains to make and use the same.

This invention relates to improvements in sand-guards for vehicle-axles. Its object is to provide a device of this character which 15 may be quickly applied to and removed from any axle and hub, which is very efficient in keeping sand and dirt from the axle-spindle, which is adjustable to suit axles of different depths, and which is simple in construction, 20 durable in use, and comparatively inexpensive of production.

With the above and other objects in view, which will readily appear as the nature of the invention is better understood, said invention 25 consists in certain novel features of construction and combination and arrangement of parts, which will be hereinafter fully described and claimed, and illustrated in the accompanying drawings, in which—

30 Figure 1 is a longitudinal sectional view through a vehicle-axle and hub, showing the application of my invention thereto. Fig. 2 is a cross-sectional view taken on the line 2-2 of Fig. 1, with parts broken away to more 35 clearly illustrate the invention. Fig. 3 is a view similar to Fig. 1, illustrating a modified form of my invention. Fig. 4 is a detail horizontal sectional view taken through the outer guard-cup, showing the manner of securing 40 the same to its supporting-bracket. Fig. 5 is a sectional view through a modified form of guard-ring.

Referring to the drawings, the numeral 1 denotes a vehicle-axle formed with the spindle 2, upon which the hub 3 of the wheel rotates. These parts may be of any construction. In order to prevent sand, dirt, water, and other foreign matter from coming in contact with the spindle, I secure upon the inner

end of the hub, concentric with the opening 50 therein, the outwardly-flaring guard-ring 4. Said ring 4, as shown in Figs. 1 and 2, is formed with an inner flange 5. Through the openings or perforations in the same the nails, screws, or other fastening means 5^a are passed 55 to fasten said ring upon the end of the hub. Instead of providing the guard-ring with an inner flange I may form the same with an outwardly-projecting circumferential flange 5^b, as illustrated in Figs. 3 and 5. 60

Upon the under side of the axle 1 I secure a supporting-bracket 6 by means of the clip 7, which straddles the axle and has its threaded ends passing through openings in the ears 8, formed upon the horizontal portion of said 65 bracket 6. Said bracket is also formed with a vertical portion 9, projecting downwardly at right angles to the horizontal portion and of greater width than the same, as shown in Fig. 4. 70

A guard-cup 10 is adapted to be supported by the bracket 6 in front of said guard-ring 4 and to project over the same. This cup may be formed as shown in Fig. 1 and extend over the ring to within a short distance 75 of the end of the hub or it may be constructed as illustrated in Fig. 3 and extend over the outside of the hub to a greater or less extent. Either form of guard-cup may be secured to the bracket 6 by forming in the 80 closed end of the cup a vertical slot or opening 11, equal in width to that of the axle and the horizontal portion of the bracket 6. The vertical walls of this slot 11 are inserted between the vertical portion 9 of the bracket 6 85 and a clamp-plate or washer 12. One or more set-screws 13 may be used to bind these parts together. By this construction it will be noted that the guard-cup 10 may be adjusted vertically, and a horizontal adjustment 90 of the same may be had by means of the clip 7.

By making the guard-cup vertically adjustable, as described, it may be readily fitted to axles of different depths. 95

The slot 11 in the guard-cup communicates with an opening 14 formed in the bottom of the same to permit the sand and dirt which

falls from the ring 4 to drop out of the cup. Said opening 14 may be of any desired shape or form.

If desired, I may make the bracket 6 without the perforated ears 8 and employ the ordinary bridge or cross plate in connection with the clip 7 to secure the bracket 6 upon the axle. If desired, I may strengthen the top of the guard-cup by screwing the same to the stock or wooden part of the axle, as shown at 10' in Fig. 3. This screw is applied after the guard is adjusted and supplements the fastening 13 to secure a firmer connection.

From the foregoing description, taken in connection with the accompanying drawings, it is thought that the construction, operation, and advantages of my improved sand-guard for vehicle-axles will be readily apparent without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

In a device of the character described, the combination with an axle and hub, of a guard-ring upon the hub, a vertically-slotted guard and cup fitted upon the axle and projecting over the ring and hub, a bracket secured to the axle and projecting through the slot of the cup to the interior thereof, and provided with a right-angular end bearing against the inner face of the cup, a clamping-plate bearing upon the outer face of the cup, and a fastening adjustably connecting the end of the bracket and clamping-plate and adjustably clamping the guard-cup between them, substantially as described.

In testimony whereof I have hereunto set my hand in presence of two subscribing witnesses.
